(57) **CLAIM**

The ornamental design for antenna whip with dual rod sets, as shown and described.

DESCRIPTION

FIG. 1 is a front elevation view of an antenna whip with dual rod sets, showing my design, the drawing also showing in phantom lines, a top which is commonly used with the antenna with dual rod sets but which does not constitute part of the design.

FIG. 2 is a rear elevation view thereof.

FIG. 3 is a left side elevation view thereof, the right side elevation view being a mirror image thereof.

FIG. 4 is a top view thereof; and,

FIG. 5 is a bottom view thereof.
